(57) **CLAIM**

The ornamental design for an automatic tablet packing machine as shown and described.

DESCRIPTION

FIG. 1 is a front-top perspective view of an automatic tablet packing machine showing our new design;

FIG. 2 is a front view thereof;

FIG. 3 is a left side view thereof;

FIG. 4 is another front-top perspective view thereof;

FIG. 5 is an enlarged view thereof showing the part 5 in FIG. 4;

FIG. 6 is another front-top perspective view thereof, shown in an environment of use;

FIG. 7 is an enlarged view thereof showing the part 7 in FIG. 6;

FIG. 8 is another front-top perspective view thereof, shown in an environment of use;

FIG. 9 is an enlarged view thereof showing part 9 in FIG. 8;

FIG. 10 is a bottom-front perspective view thereof, shown in an environment of use;

FIG. 11 is an enlarged view thereof showing part 11 in FIG. 10;

FIG. 12 is another bottom-front perspective view thereof, shown in an environment of use; and,

FIG. 13 is an enlarged view thereof showing the part 13 in FIG. 12.

The broken lines in the drawings illustrate portions of the automatic tablet packing machine which form no part of the claimed design.

1 Claim, 13 Drawing Sheets
